UNITED STATES PATENT OFFICE.

JOSE RIERA HERNANDEZ, OF HAVANA, CUBA.

CIGARETTE-WRAPPER HOLDER.

SPECIFICATION forming part of Letters Patent No. 521,026, dated June 5, 1894.

Original application filed September 15, 1893, Serial No. 485,542. Divided and this application filed December 5, 1893. Serial No. 492,871. (No model.)

To all whom it may concern:

Be it known that I, JOSE RIERA HERNANDEZ, a subject of the King of Spain, and a resident of Havana, in the Island of Cuba, have 5 invented certain new and useful Improvements in Cigarette-Wrapper Holders, of which the following is a full, clear, and exact specification.

My present application is a division from 10 that filed by me in the Patent Office on or about September 15, 1893, Serial No. 485,542 and on which a patent was issued March 13, 1894, No. 516,392, and relates to a wrapper holder which is adapted to hold and smooth 15 cigarette wrappers before the same are rolled around the filler.

My invention consists of certain features of construction, and combinations of the same, as will be fully described hereinafter and pointed 20 out in the claim.

Reference is had to the accompanying drawings in which like numerals indicate corresponding parts throughout the several views.

Figure 1 is a sectional elevation of the improvement on line 1-1 of Fig. 2. Fig. 2 is a plan view of the same; and Fig. 3 is a front elevation thereof.

The improved wrapper holder is usually arranged on a table 1, supported on legs or 25 standards 2, and having a rear wall 3 and side walls 4. The holder consists primarily of a bottom board or foundation plate 5 forming a table at the rear of which are secured uprights 6 supporting an axle 27 that extends 30 longitudinally of the foundation plate. On the said axle are loosely mounted levers 28, the rear ends whereof are connected by means of cords 29, passing over guide pulleys 24, with pedals 30 pivoted at the front end of the 35 machine. The front ends of the levers have a pivotal connection of any suitable kind with plungers 31 to which are secured rings or loops 32 adapted to move along guides 33, the said rings being preferably pivotally connect- 40 ed with the plungers to allow the latter to assume a slight inclination. A spring 34, serves to return the plunger toward the table after it has been raised by depressing the corre-

sponding pedal 30. The width of the plungers 31 is equal to the length it is intended to 50 give the cigarette wrappers.

The operation of the machine is as follows: The cigarette wrappers 7 which are not yet of the exact length desired, are stretched out and spread smooth on the table and brought 55 one after the other under one of the plungers 31, it being understood that the corresponding pedal 30 is depressed in order to raise the plunger. As soon as the pedal is released, the plunger is brought down on the wrapper 60 by the spring 34 and will hold it firmly and smoothly on the table until the plunger is raised another time to place the following wrapper on the top of the first. This operation is continued till a great number—say 65 three hundred to four hundred wrappers are piled beneath the plungers 31. It will be obvious that the wrappers will be held perfectly smooth and after being cut down to the exact length will be ready to be wound or rolled 70 on a tobacco filler. The material for the wrappers may be paper or tobacco leaves.

It will be obvious that the foundation plate 5 may be omitted, and the uprights 6 and guides 33 secured directly to the table 1. 75

What I claim, and desire to secure by Letters Patent, is—

A cigarette wrapper holder, comprising a table on which the wrappers are adapted to be laid, uprights rigidly connected with the 80 table, a lever pivotally connected with the uprights, a pedal operatively connected with the rear arm of the lever, a plunger having a pivotal connection with the front arm of the lever, a ring pivotally connected with the 85 plunger and extending approximately perpendicular thereto, a guide secured to the table and arranged parallel to the plunger to be engaged by the said ring, and a spring for pressing the front arm of the lever toward 90 the table, substantially as described.

JOSE RIERA HERNANDEZ.
